[57] CLAIM

The ornamental design for a hat, as shown and described.

DESCRIPTION

FIG. 1 is a top plan view of a hat showing our new design;

FIG. 2 is an elevational view taken in the direction of arrow 2 shown in FIG. 1;

FIG. 3 is an elevational view taken in the direction of arrow 3 shown in FIG. 1;

FIG. 4 is an elevational view taken in the direction of arrow 4 shown in FIG. 1;

FIG. 5 is a bottom plan view thereof.

FIGS. 1-4 are shaded for color contrast.

FIG. 1.

FIG. 2.

FIG. 3.

FIG. 5.

FIG. 4.
